CRUTCH

Harris A. Tracy, Stoughton, Mass.

Application January 20, 1945, Serial No. 573,662

2 Claims. (Cl. 135—51)

My invention relates to improvements in crutches, for walking purposes, the primary object in view being to provide a simply constructed, inexpensive crutch particularly adapted to support the weight of a body through the medium of the arms of the user and the hands, instead of solely from the shoulders, and which is easy to handle, provides for minimum strain on the hands, is strong and safe, and adequately cushioned so as to render the use thereof less tiring than ordinary crutches.

Other and subordinate objects are also comprehended by my invention, all of which, together with the precise nature of my improvements, will be readily understood when the succeeding description and claims are read with reference to the drawing accompanying and forming part of this specification.

In said drawing:

Figure 1 is a view in side elevation of my improved crutch, in its preferred embodiment,

Figure 2 is a fragmentary view in longitudinal section, taken on the line 2—2 of Figure 1, and drawn to an enlarged scale.

Figure 3 is a view in transverse section taken on the line 3—3 of Figure 1.

Referring to the drawing by numerals, my improved crutch, as illustrated, comprises the usual rounded staff portion 1 from which rises a pair of like yoke-forming side members 2 of the usual type, but split at their juncture with the staff portion 1 from the material of which the crutch is made, preferably wood. A rivet 3 is extended through the staff portion 1 at the juncture thereof with the side members 2 to prevent said staff portion 1 from splitting downwardly from said side members.

A cross bar of suitable material, preferably wood, and designated 4 extends between the side members 2 and at a suitable distance from the upper ends of said side members 2 to provide, together with said ends, a comparatively deep crotch 5 at the upper end of the crutch. The cross bar 4 is preferably formed with a relatively deep, concave upper edge 6. A cross rod 7 extending through the side members 2 and the cross bar 4 with riveted ends 8 secures the said cross bar and said side members 2 together.

Substantially midway, preferably, between the cross bar 4 and the staff portion 1, a pair of upper and lower, transverse hand grips 9, 10 of convex form longitudinally are fitted endwise between the side members 2 in closely adjacent relation and parallel, with rods 11, 12, similar to rod 7, extending therethrough and through said

side members 2 to secure the hand grips in position. The hand grips 9, 10 may be nested, one in a concavity 13 provided in the other to arrange said grips close together.

At the lower end of the staff portion 1, a cylindrical socket member 14 is provided and which is formed of suitable resilient material, such as rubber. The socket member 14 is divided by a diametrical web 15, relatively thick, into a comparatively deep upper socket 16 by means of which said member is sleeved onto the staff portion 1, and a shallower bottom socket 17 in which is fitted a cushion tip 18 of softer resilient material than that of the socket member 14, for instance, soft rubber. A spike 19, or nail, having its head 20 suitably embedded in the tip 18 extends upwardly through the partition 15 and into the staff portion 1 and secures the socket member 14 to said staff portion, and the tip 18 in the socket 17.

In using the described crutch, the crotch 6 is suitably positioned under the arm and straddles the upper portion of the arm at the inner side thereof below the shoulder, the hand grasping the hand grips 9, 10. With the crotch so positioned, the entire weight of the body may be borne by the arms and the crutch may be held conveniently so as to prevent the crotch 6 from becoming displaced from proper position around the arms. The described double hand grip surface, than in the usual crutch, obviating closing of the hand tightly and thereby cramping the palm and fingers. The socket 14 and tip 18 provide inexpensive effective means for cushioning the crutch which may be easily and inexpensively replaced as required.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claims.

What I claim is:

1. A crutch comprising a staff portion, a pair of yoke-forming side members rising from said staff portion, a cross bar extending between said side members below the upper ends of said members and forming with said upper ends a deep crotch for straddling the arm of the user, and a pair of superposed hand grips extending between said side members below said cross bar and ar-

ranged close together for circumposition by a hand around the same.

2. A crutch comprising a staff portion, a pair of yoke-forming side members rising from said staff portion, a cross bar extending between said side members below the upper ends of said members and forming with said upper ends a deep crotch for straddling the arm of the user, and

a pair of superposed hand grips extending between said side members below said cross bar and arranged close together for circumposition by a hand around the same, one of said hand grips having a concavity therein and the other hand grip nesting in said concavity to dispose said grips close together.

HARRIS A. TRACY.
